UNITED STATES PATENT OFFICE.

FREDERIC SCHAEFER, OF PITTSBURGH, PENNSYLVANIA.

ELECTRIC SIGN.

1,039,582.

Specification of Letters Patent.

Patented Aug. 5, 1912.

Application filed November 11, 1911. Serial No. 652,724.

To all whom it may concern:

Be it known that I, FREDERIC SCHAEFER, a resident of Pittsburgh, in the county of Allegheny and State of Pennsylvania, have invented a new and useful Improvement in Electric Signs, of which the following is a specification.

This invention relates to electric signs, and more particularly to that class of signs in which symbols are successively displayed, such as the successive displaying of letters of the alphabet for the purpose of spelling out any word, phrase or sentence.

The invention is well adapted for displaying bulletins for campaigns, newspaper work, etc., or for advertising or other similar purposes.

The purpose of the invention is to provide an apparatus and system for the purpose stated which is of simple construction as far as the display or sign unit is concerned and in which the system can be readily operated either automatically or by hand.

The invention comprises the construction and arrangement of parts hereinafter described and claimed.

In the accompanying drawings Figure 1 is a face view of one form of a sign or display unit; Fig. 2 is in part a side view and in part a vertical section on the line 2—2, Fig. 1; Fig. 3 is a face view showing a portion of a modified form of sign or display unit; Fig. 4 is a vertical section on the line 4—4, Fig. 3; Fig. 5 is a face view of a sign having several different kinds of units therein; Fig. 6 is a face view of still another form of display unit; Fig. 7 is a diagrammatic view of wiring for operating the display units, showing the same in simple or elemental arrangement; Fig. 8 is a diagrammatic view of another arrangement of wiring for actuating the display units and in which an automatic selective switch is used; and Fig. 9 shows another arrangement of group switch with means for actuating the automatic selective switch.

The sign is composed of a series of units, all alike and each comprising a considerable number of simple display elements or shutters with a magnet for actuating each thereof and so arranged that by setting different

combinations of these display elements a shutters different symbols, letters or figures are displayed by each of the units.

As shown in Figs. 1 and 2, each unit is composed of 35 display devices 11, with a corresponding number of double solenoids 12—13 for actuating the same. Each pair of solenoids surrounds a suitable bobbin 14 in which works the core 15 for actuating the display device or shutter 11, one solenoid of each pair serving to move the display device to "visible" position and the other to move the same to "invisible" position, as will be readily understood. The set of solenoids are held between a front plate 16 and a rear plate 17, which plates are held in suitable spaced position by means of bolts 18 surrounded by spacing sleeves 19. These bolts also serve as means for securing the unit to the supporting frame shown diagrammatically in Fig. 2 as comprising two metal angle bars 20. This simple construction enables the units to be readily assembled or taken apart and is also quite inexpensive. Preferably both face plates are flanged on their side edges to stiffen the same and enable them to be made of relatively thin metal. The edge flanges of the rear plate are indicated at 21 and those of the front plate at 22.

The display members or shutters may be of a variety of forms, either any of the various forms which are now used for various display purposes in electrical apparatus, or of the forms shown in the drawings.

In the drawings two forms of display devices are shown. In Figs. 1 and 2 the display devices are shown in the form of cylindrical members pivotally or rotatably mounted on axes 23 extending between the edge flanges 22 of the front plate 16. Each of these members has a display face 24 and a blank face 25 which generally are merely of different colors. On the blank or rear side of these display devices is a slot 26 into which projects the end of a connecting member 27 secured to the solenoid core 15 and pivotally secured to the display cylinder. Obviously when the solenoids 12 are energized the cores 15 are moved outwardly, as shown at the top of Fig. 2, to expose one

face of the display device, while when the solenoids 13 are actuated the cores are moved inwardly to the position shown in the second from the top solenoid in Fig. 2 to expose 5 the other face of the display device. Since each solenoid of the group of solenoids composing the unit is capable of separate energization it is possible to expose the "visible" or display faces of any desired combination of display devices, as, for instance, in Fig. 1 where the letter F is represented, or as shown in Figs. 5 and 6, where various other letters are represented. As illustrated in Fig. 2, each core 15 is reduced at each end 10 and moves loosely in the bobbin 14 of its solenoid, so that it can slide easily endwise and also tilt sidewise, thus compensating for the movement of the end of its extension in the arc of a circle around the pivot of the 15 display member. In other words, as each core moves endwise, the angular relation of its axis varies with relation to the axis of its core.

Figs. 3 and 4 show a modification where- 20 in the display devices 11^a comprises a display face 24 and blank face 25 arranged at an acute angle to each other and also pivotally or rotatably mounted, as in Fig. 1 and connected to the solenoid core 15, as clearly 25 shown, by a pin and slot connection 26^a. The operation of this form is identical with the form shown in Figs. 1 and 2.

The display faces of the several display devices or shutters can be of any suitable 30 color, and the surrounding frame part of the sign is preferably of the color of the blank faces. For instance, in Fig. 5 the unit A has the frame and blank faces black, while in the 35 unit B the reverse is the case, and in the unit C the frame and blank faces are white and the display faces are of different color. The number of display devices can of course be increased to any desired number. Fig. 5 40 represents each unit composed of 30 shutters or display devices, by different combinations of which every letter of the alphabet can be represented. Fig. 6 shows the 45 unit composed of a very much larger number of display devices, 252 in all.

Various arrangements of wiring system and circuit closers can be used for actuating the desired group of magnets in each unit in order to display or spell out the desired 50 symbol, word or message. The circuits of the several magnets may be closed, in the proper order or sequence entirely automatically, such as from a motor driven rotary drum having thereon the necessary projections for closing the various circuits in the proper group relations.

Fig. 7 represents a simple arrangement of circuits and hand-actuated circuit closers for securing the desired result. In this dia-

gram only three units are shown and only 65 four of the double magnets, to-wit, four setting magnets 12 and four re-setting magnets 13, but the principle applies to any number of such magnets. 30 represents a suitable group circuit closer 70 which may be actuated in any suitable way, such, for instance, as from a key board like a typewriter key board and so arranged as to close the desired group of circuits to each of the units. 31, 31^a and 31^b represent 75 selective switches, one for each of the units. 32 is the re-setting switch and 33 a suitable source of electric energy. When the selective switch 31 is closed, the closing of group switch 30 closes the circuit from the battery through the setting magnets 12 of unit A, and by properly closing selective switch 31^a and 31^b the closing of group switch 30 directs the current through the setting magnets 12 of units B and C respectively. There is, therefore, one selective switch for each unit, and there must be as many group switches 30 as the letters or symbols to be displayed on each of the units. By closing the proper selective switch and the proper group switch the desired letter or symbol is shown on the desired unit. When re-setting switch 32 is closed the current from battery 33 is directed through the re-setting coils 13 of each of the magnets. 95 A single re-setting switch for the entire series of units is sufficient.

Fig. 8 represents a further development of this elemental system. In this diagram there are four units shown, to-wit, A, B, C 100 and D, each composed of four double magnets, that is, four setting magnets 12 and four re-setting magnets 13. The group switch is indicated at 30^a and when closed directs the current from battery 33 through the group of setting coils 12 for which said group switch is arranged in the particular unit to which the circuit is closed by the selective switch. The selective switch shown comprises an arm 36 arranged to travel over a circularly arranged series of contacts 37 each of which is connected to one of the units of the sign. This arm is adapted to be rotated clockwise by means of ratchet wheel 38 and pawl 39, the latter being actuated from armature 40 of magnet 41 in the circuit with battery 33, but which magnet is energized by actuation of each group switch 30^a. As shown, this is effected by providing the group switch 30^a with a contact projection 42 arranged to contact a yielding arm 43 connected to one terminal of magnet 41 so that whenever group switch 30^a is actuated to close the circuit to a certain group of magnets, say in unit A, the magnet 41 is 115 energized slightly in advance of closing the group circuits to step the selective switch 36 one step forward to connect the desired unit 120

in circuit. Hence the successive actuations of the group switch closes the circuit to successive units.

Fig. 9 illustrates another modification wherein the selective switch 36 is mechanically actuated directly from the group circuit closer 30^a, by having the pawl actuating rod 45 connected to a projecting end 46 of the switch actuating arm. A crank 37^a 10 on the shaft of the ratchet wheel 38 enables the selective switch to be set by hand to bring into circuit the desired unit. This view also shows the group switch actuated from a device resembling an ordinary typewriter. This view shows three type bars 15 with actuating members 47, 48 and 49. The dots 50 represent contacts for the series of wires going to each of the units of the sign. Each lever carries a contact member 51 of 20 such size as to contact with the desired number of contacts 50 to close the circuit to the group of magnets necessary to represent the letter or symbol of the particular key which is depressed. There will be as many keys 25 as symbols or letters to be represented, and each key controls a different arrangement or combination of groups of magnets in each of the units of the sign. A single key board of group switches only is necessary for the 30 whole sign and a single re-setting switch alone is necessary, connection to the desired units of the sign being successively and automatically effected by selective switch 36. It is therefore possible for an operator actuating the keys, much as in a typewriter, 35 to spell out upon the sign any desired word, symbol, or group of words or symbols to display any bulletin or other message intended to be displayed. The selective switch of course breaks the circuit to any one unit as soon as the next group switch is closed, but as the setting magnets of the prior unit have been energized, and as the display devices or shutters of the units are 40 mechanical and not electric, such as an electric light, the letter or symbol which has been set remains displayed until the re-setting key 32 is closed. The entire sign, therefore, may be retained in visible condition as long as desired.

All parts of the entire system are quite simple and inexpensive to construct and easy to operate. When displaying advertisements or other matter which is displayed 45 in rotation the various group circuit closers can be actuated from some mechanical means, such as a drum or the like and complete sentences made to appear at once. For displaying bulletins, for instance, such as 50 election returns, or foot ball returns, the various group switches will be operated by hand, in a manner similar to the operation of the key board of an ordinary typewriter.

Various modifications can be made par-

ticularly in the forms and arrangement of 65 the various circuit closers and switches without departing from the invention herein-after claimed.

What I claim is:—

1. An electric sign or display unit comprising a plurality of solenoids, front and back plates engaging the ends of said solenoids, means tying said plates together and thereby clamping the solenoids in position between said plates, cores in said solenoids provided with extensions projecting through the front plate, and display members or shutters outside of said plate and actuated from said cores. 70

2. An electric sign or display unit, comprising a frame having a substantially vertical face plate provided with apertures therethrough, a plurality of double solenoids carried by said face plate and supported on the rear side thereof with their axes normal thereto, the units of each double solenoid being in axial alignment, a core loosely movable in each of said double solenoids and provided with an extension projecting through one of said apertures in 80 the face plate, display members movably mounted on the front side of said face plate and each connected to be actuated by one of said extensions, and means arranged to close circuits to said solenoids, whereby the 85 momentary energization of a solenoid shifts a display member and the same is held in said shifted position until the energization of the other solenoid of the pair. 90

3. An electric sign or display device comprising a frame, a plurality of solenoids mounted in said frame with their axes normal to the front face of the frame, display members pivotally mounted on the front face of the frame on axes normal to the axes of the solenoids, a core loosely movable in each solenoid, and an operative connection between each solenoid core and a display member and arranged with a pivotal connection to said display member so located that in all positions of the display member a plane intersecting said pivotal connection and the axis of the solenoid core is at one side of the pivotal mounting of the display member. 100

4. An electric sign or display unit comprising a frame including a front plate, side flanges on said front plate, display devices pivotally supported between and by said side flanges, a plurality of solenoids in said frame, and a core in each of said solenoids operatively connected to a display device. 105

5. An electric sign or display unit comprising front and back plates, a plurality of multiple solenoids therebetween, means for securing said front and back plates together and clamping said solenoids therebetween, a core in each pair of solenoids, side flanges 110

115

120

125

projecting forwardly from said front plate, and display devices pivotally supported between and by said side flanges and arranged for actuation by said cores.

- 5 6. An electric sign or display unit comprising a frame, a plurality of double solenoids in said frame, a core loosely movable in each of said double solenoids, a rotatable display member mounted on said frame adjacent to each double solenoid, each of said cores having a rigid extension pivotally

connected to a display member, and each core being reduced at its ends, whereby in moving endwise in its solenoid the core may tilt with relation to the axis of the solenoid. 15

In testimony whereof, I have hereunto set my hand.

FREDERIC SCHAEFER.
